Primary Examiner—Louis S. Zarfas*Assistant Examiner*—Robert A. Delehanty**(57) CLAIM**

The ornamental design for a reusable produce crate lid, as shown and described.

DESCRIPTION

FIG. 1 is a perspective view of a reusable produce crate lid showing my new design;

FIG. 2 is an alternate perspective view thereof; and, FIG. 3 is a top plan view thereof.

The broken line structure in FIGS. 1-3 showing various elements and features of the reusable produce crate lid is for environmental purposes only and forms no part of the claimed design.
